UNITED STATES PATENT OFFICE

JOSEPH RICE, OF CHICAGO, ILLINOIS, ASSIGNOR OF ONE-HALF TO ELEVATOR MFG. COMPANY OF AMERICA, OF CHICAGO, ILLINOIS, A CORPORATION OF ILLINOIS

MOVABLE PLATFORM CONSTRUCTION

Application filed August 17, 1931. Serial No. 557,506.

My invention relates to platform constructions similar to that shown in my prior Patent No. 1,687,794 on Movable floor for elevator cars.

5 It is the main object of this invention to provide a construction whereby when a person steps off the entrance threshold they at once step on the floating platform.

In this connection, my invention contemplates the provision of a floating sill extending outside the frame which carries the floating platform whereby any part available for a person to step upon from the entrance threshold is movable with the floating platform or floor. This eliminates any danger of the weight of the person not being applied to the movable platform and insures safer operation.

It is also a purpose of this invention to provide a novel means of mounting the movable sill whereby to cause it to follow the movable floor or platform.

A further object of the invention is to provide a novel combination between the door guide or track and the floating sill and floor whereby the guide is held stationary while the sill and floor move together.

I will describe the preferred form of my invention by reference to the accompanying drawing wherein—

Fig. 1 is a horizontal cross section through an elevator car embodying my invention;

Fig. 2 is a vertical section through the movable floor and framework construction; and

Fig. 3 is an enlarged detailed view of the sill mounting.

Referring now in detail to the drawing, the numeral 5 indicates the usual elevator car having a gate 6, a threshold 7, and a floor 8. This floor is of the movable type such as is shown in my prior patent. That is to say, the floor 8 is carried by means of a framework 9 which framework has fixed thereto the bearings 10 and 11 forming inclined surfaces for the ball bearings 12. Floor 8 and its supporting structure have the depending bearing portions 13 and 14, and of course suitable counterbalance mechanism such for example as the weight 15 on the bell crank

16 may be used to hold the floor in the position shown in Fig. 2. It is clear, of course, that if weight is added to the floor 8 as by people stepping thereon, this floor will be moved downwardly and to the left as shown 55 in Fig. 2. In my prior patent, the function of this movement is to operate the control mechanism for an elevator car or similar device.

In order to have the least amount of space 60 possible between the edge of the floating platform and the edge of sill of the entrance door so that when the entrance door is closed there is no possibility of a person's foot being off the floating platform, I preferably 65 provide a sill member 17 which as shown extends across the front of the frame 9 and is provided with a ledge at 18 sufficiently spaced from the floor 8 to allow for operation of the door guide therebetween. 70

Now in order to insure the support of the sill 17, I connect it to the frame 20 of the floor 8 for example in the manner shown in Fig. 2, that is, by means of a series of brackets such as indicated at 21. These brackets, of course, must be strong enough and rigid 75 enough to maintain the sill 17 rigidly in position under all service conditions.

An important feature of the invention is the mounting of the sill so that the door 6 80 has a stationary track while the sill and platform move. I provide an opening 22, and the guide member 23 on the door 6 extends down into the track 24 which is stationary on frame 9. This permits the sill and floor to move without affecting the door operation on the track 24. 85

From the above description, it is believed to be clear that I have provided a simple 90 floating sill construction whereby a sill piece moving with the moving floor of the platform construction may be readily supported in such position as to provide an adequate protection against danger at the point where the movable floor edge passes over the supporting frame. 95

Having thus described one specific form of my invention, what I claim as new and desire to secure by Letters Patent is:

1. In a platform construction, a framework 100

and a floor carried thereby and movable laterally thereon, means for movably carrying said floor on said framework, a sill for said floor outside said framework, a door on said framework between the sill and floor, and means connecting said sill and floor whereby they are movable together relative to said framework.

2. In a platform construction, a framework and a floor carried thereby and movable laterally thereon, means for movably carrying said floor on said framework, a sill for said floor outside said framework, said framework having a closure support on the top thereof between the sill and floor, and means passing through said framework connecting said sill and floor whereby they are movable together relative to said framework.

3. In a platform construction, a framework and a floor carried thereby, means for movably carrying said floor on said framework, a sill for said floor outside said framework, and having a ledge portion spaced from said floor but substantially level therewith, and means connecting said sill and floor whereby they are movable together relative to said framework.

4. In a platform construction, a framework and a floor carried thereby, means for movably carrying said floor on said framework, a sill for said floor outside said framework and having a ledge portion spaced from said floor but substantially level therewith, and means passing through said framework connecting said sill and floor whereby they are movable together relative to said framework.

5. In a platform construction, a framework and a floor carried thereby and movable laterally thereon, means for movably carry-

ing said floor on said framework, a sill for said floor outside said framework, said sill and floor being spaced apart over the framework, and means below said floor rigidly connecting said sill and floor whereby they are movable together relative to said framework.

6. In a platform construction, a framework, a floor, means for movably carrying said floor on said framework, a sill for said floor outside said framework, a door above said floor and sill having a track on said framework, means connecting said sill and floor whereby they are movable together relative to said framework without interfering with the door moving on its track.

7. In a platform construction, a framework and a floor carried thereby, means for movably carrying said floor on said framework, a sill for said floor outside said framework, and means connecting said sill and floor whereby they are movable together relative to said framework, a door above said floor having a guide track on said framework, and guide means on said door projecting through the plane of said floor and sill to said track.

8. In a platform construction, a framework and a floor carried thereby, means for movably carrying said floor on said framework, a sill for said floor above said framework, and means connecting said sill and floor whereby they are movable together relative to said framework, a door above said floor having a guide track on said framework, and guide means on said door projecting through the plane of said floor and sill to said track.
